TORVAL J. ANDERSON, OF CHICAGO, ILLINOIS

SHAPER HEAD FOR WOOD WORKING MACHINES

Application filed February 18, 1929. Serial No. 340,895.

With the shaper heads for wood working machines now on the market, the knives are held in place by the clamping blocks only, with no means whatever for holding the knives in place or against outward movement, except the clamping action of the blocks. With such a construction the knives are not infrequently thrown from their mounting when rotating at a high speed with the likelihood of disastrous results, either due to the fact that the clamping blocks wear or become loose or the knives have been ground down and adjusted upwardly to such an extent that there is only a small portion gripped by the blocks. Moreover, with such a construction there is a tendency of the knives, when in operation, to shear the grooves in which they are mounted, thus not only throwing them out of alignment and causing them to chatter or vibrate, but to become loose, permitting them to be thrown, with the likelihood of endangering the operator. Therefore, it is an object of my invention to provide a shaper head for wood working machines which overcomes these disadvantages and objections, and to provide in combination with a shaper head, means for positively preventing the throwing of the knives from any of these causes, and to positively limit the outward movement of the knives from any of these causes. It is a further object to provide in combination with a shaper head of this class, means which prevents the knives from becoming out of alignment or shearing the means in which they are mounted.

It is a further object to provide an evenly balanced cylindrical, enclosed shaper head which, when in operation, materially reduces the viscosity of the air and materially lends itself to smoothness of operation, eliminating vibration and chatter, and affords an even rotary balance. It is a further object of my invention to provide a knock down shaper head for wood working machines with improved means for mounting and for limiting the adjustment of the knives, with all the parts removably clamped within a cylindrical casing. It is a further object to provide equalizers that will

move in accordance with the knives and to properly balance one knife with respect to the other should they become out of balance, due to grinding, or otherwise.

The above and other features of novelty, 55 advantages and capabilities will become apparent from a detailed description of the accompanying drawings in which I have illustrated my invention, but the constructions there shown are to be understood as illustrative and not as defining the limits of my invention.

Fig. 1 is a sectional view of the shaper head, embodying one form of my invention, taken substantially on the line 1—1 of 65 Fig. 3.

Fig. 2 is a sectional view taken substantially on the line 2—2 of Fig. 3.

Fig. 3 is a sectional view taken on the line 3—3 of Fig. 1.

Fig. 4 is a sectional view on the line 4—4 of Fig. 1.

Fig. 5 is a sectional view taken on the line 5—5 of Fig. 6.

Fig. 6 is a view of the cylindrical casing. 75

Fig. 7 is a side elevation view of the slotted frame in which the knives are adjustably mounted.

Fig. 8 is a perspective view of the traveling block on which the knives are mounted. 80

Fig. 9 is a perspective view of an equalizer for balancing one knife with respect to the other.

Fig. 10 is a perspective view of one of the knives showing the oblong opening near one 85 end thereof.

Referring to the form illustrated in the ten figures of the drawings, the device comprises a cylindrical casing 11, provided with an integral end 12 with a suitable opening 90 to receive the spindle 13 of the machine. Loosely mounted in the casing 11 is a pair of disks 14, one of which is in contact with the end 12 of the casing 11 and the other being adapted to be engaged by the nut 17. These 95 disks are provided with openings for receiving the spindle 13 and are loosely mounted thereon so that they can be readily and quickly removed from and replaced on the spindle whenever desired. The disks 14 are 100

provided, at an angle to the axis thereof, with a pair of opposed beveled grooves 16 for receiving the longitudinal beveled edges of the knives 15, as best shown in Fig. 2. 5 Fixed to the spindle 13, is a collar 30 against which the end 12 of the casing abuts. By properly turning up the nut 17 the disks 14 are caused to tightly clamp the knives therebetween in the grooves heretofore mentioned, over a considerable portion of the 10 length of the knives for properly and securely holding them in place against vibration or "chattering". For receiving the end of the knives and permitting them to be 15 swung into position, the casing 11 is provided with diametrically opposed slots 16^a, Fig. 6. As a result of this arrangement, when the spindle is being operated, and the shaper in use, the driving power is applied 20 throughout the greater portion of the length of the knives, thus minimizing the lever action, and eliminating the vibration inherent in the old types. The outer disk 14 is provided with tongues or lugs 18 which 25 are adapted to register with and completely fill the opposed slots in the casing after the knives have been positioned, and in addition, to cause said disk 14 to drop into position and to rotate with the casing. 30 I will now describe the means for adjusting or setting the knives. Mounted within the casing 11, between the disks 14, is a rectangular frame comprising heads 19 and side members 20. The side members are 35 provided with longitudinal slots 21, terminating at opposite ends, with an enlarged circular opening 22. The heads 19 are provided with suitable openings 23 to receive the screws 24 to hold the rectangular frame 40 in position on the lower disk 14. The lower disk 14 is provided with suitable openings 31 to receive the pins 33 on the inner end 12, so that the disk and rectangular frame are caused to rotate with the casing. The traveling block 25 is provided with a shoe 25^a 45 adapted to slide in the slots 21. Extending beyond the shoe is an integral pin 26 on which is pivotally mounted the knives 15. The pin 26, near its outer end, is provided 50 with opposed notches, and the member 27 has a suitable slot 29 adapted to interlock with the notched portion of said pin. Formed integrally with the locking member 55 27 is an equalizer 28, which fits against the end of the knives and in reality forms an extension thereof, and in practice is made of varying thicknesses to afford different weights, so that when one knife becomes 60 slightly lighter than the other, due to grinding, or otherwise, they can be readily put in balance by selecting a locking member and equalizer of the proper weight. This is important, for in practice these knives 65 readily become out of balance, due to wear

or grinding, and when once out of balance, do not operate properly.

The openings 32 in the knives 15, for receiving the pin 26 are oblong in shape, as best shown in Fig. 10, so that they may be 70 attached and detached without removing the rectangular frame from the casing. When it is desired to remove the knives, all that is necessary, after removing the outer disk 14 is to withdraw the locking member 75 27 and swing the knife to a position in alignment with the plane of the spindle shaft, and then move the inner end of the knives outward, away from the traveling block.

From the description thus far it will be 80 seen that I have provided a shaper head which entirely encloses the means for limiting the outward adjustments of the cutting knives and prevents any likelihood of the parts becoming loose, tightly clamps the 85 knives, and affords driving power throughout the greater portion thereof, and provides an even rotary balance.

It will be noted that in my shaper head the 90 traveling block on which the knives are pivotally mounted, absolutely prevents the knives from being thrown from the head, for the outward movement of the knives is checked when traveling blocks come into engagement with the ends of the adjusting 95 frame. Furthermore, it will be seen that with the enclosed shaper head the walls of the longitudinal slots are in tight engagement with the sides of the knives, thus preventing the knives from twisting in or from 100 shearing the grooves in the clamping blocks when abnormal strains are imposed thereon.

Having thus described my invention, I claim:

1. In a shaper head, the combination of 105 opposed clamping members adapted to be mounted on a spindle shaft; a frame provided with longitudinal slots connected to one of said clamping members; traveling blocks slidably mounted in said slots; cutting 110 knives provided with an opening near their inner ends mounted between said clamping members, said blocks provided with pins that register with the opening in said knives.

2. In a shaper head, the combination of 115 opposed clamping members adapted to be mounted on a spindle shaft, and provided on their opposed surfaces with cooperating spaced grooves; a frame provided with longitudinal slots connected to one of said clamping members; traveling blocks slidably mounted in said slots; cutting knives provided with an opening near their inner ends mounted in said grooves between said clamping members; pins on said blocks, said pins extend through an opening in said knives, and equalizers that form an extension of said knives are connected to said pins to balance one knife with respect to the other.

3. In a shaper head for wood working ma- 130

chines, the combination of a cup like casing provided with combined knife and lugs receiving open slots extending longitudinally from the open end of said casing to a point adjacent the opposite end so as to permit shaping knives to move into position from the top of said casing; opposed clamping members, one of said members provided with lugs adapted to register in said slots and move into position from top of said casing; said lugs extend through the open slots and form a flush gauging surface with the outside of said casing.

4. In a shaper head, the combination of opposed clamping members adapted to be mounted on a spindle shaft, cutting knives provided with an opening near their inner ends mounted between said clamping members, a frame positioned between said knives and connected to one of said members, and traveling blocks connected to said knives and mounted in said frame to limit the sliding movement of said knives.

5. In a shaper head, the combination of an open slotted cuplike casing adapted to be mounted on a spindle shaft, opposed clamping members within said casing, cutting knives provided with openings near their inner ends mounted between said clamping members, a frame in said casing, positioned between said knives, traveling blocks provided with pins adapted to register in the openings in said knives and slidably mounted in said frame to limit the outward movement of said knives.

6. In a shaper head for wood working machines, the combination of a spindle shaft, an open slotted round cup-like casing adapted to be mounted on said shaft, opposed clamping members also adapted to be mounted on said shaft, cutting knives mounted between said clamping members and extending through the open slots in said casing, one of said members provided with lugs adapted to register in the open slots in said casing, slidable means mounted on the bottom member for limiting the outward movement of said knives, and a nut on the end of said shaft for tightly clamping said knives in position and said members and said casing to said shaft.

7. In a shaper head, a frame mounted in said head, slidable means in said frame, cutting knives in said head provided with openings near their inner ends, said means connected to said knives to limit the outward movement of said knives, and equalizers connected to said means to balance one knife with respect to the other.

80 TORVAL J. ANDERSON.
